UNITED STATES PATENT OFFICE.

KATHRINE ROHRDANTZ, OF BUFFALO, NEW YORK.

WAX-HOLDER.

No. 817,275.

Specification of Letters Patent.

Patented April 10, 1906.

Application filed February 28, 1905. Serial No. 247,710.

To all whom it may concern:

Be it known that I, KATHRINE ROHRDANTZ, a citizen of the United States, residing at Buffalo, in the county of Erie and State of New York, have invented new and useful Improvements in Wax - Holders, of which the following is a specification.

This invention relates to wax - holders which are used for holding wax in applying ¹⁰ the same to sad-irons.

The object of this invention is the production of a wax - holder having a fastener whereby the same may be readily secured to a support within convenient reach of the operator, which fastener also serves as the ¹⁵ means for adjusting the wax in the holder as the wax is consumed.

In the accompanying drawings, Figure 1 is a side elevation of my improved wax-holder ²⁰ applied to the edge of an ironing board or table. Fig. 2 is a vertical longitudinal section of the same on an enlarged scale. Fig. 3 is a top plan view thereof. Fig. 4 is a bottom plan view thereof with the fastener removed. Fig. 5 is a perspective view of the fastener.

Similar letters of reference indicate corresponding parts throughout the several views.

A represents the wax-cake, which is preferably of cylindrical form and arranged loosely within an inclosing receptacle or box B. The top of this box is closed by a covering C, of loosely-woven fabric or other open-mesh or porous material. This covering is lapped at its margin or edge downwardly around the outer side of the box and is held in place on the same by a retaining band or ring D, which is slipped over the lapping edge of the covering and confines the latter frictionally between the outer side of the box and the inner side of said band. Centrally in its bottom a the box is provided with an opening e, through which projects the head F for adjusting the wax in the box. This head bears at its upper end against the under side of the wax-cake, a protecting disk or sheet g being preferably interposed between the under side of the wax and the upper side of the ³⁵ adjusting-head, as shown in Fig. 2. At its lower end the adjusting-head is connected with a clamp H, whereby the head and the parts carried thereby may be detachably connected with the edge of an ironing board, table, or similar support I. This clamp is ⁴⁰ substantially U-shaped, and consists of upper

and lower horizontal clamping - jaws h h', which are connected by a flexible bow or arch h² and the upper one of which carries the adjusting-head. The fastening-clamp and adjusting-head are preferably constructed from ⁶⁰ a single strip of spring metal, one end of which is bent upon itself to form the upper jaw, the lower jaw, and the bow of the clamp, while its other end is bent in the form of a rectangular eye or loop, which constitutes ⁶⁵ the adjusting-head and which consists of a straight horizontal top f, a straight vertical side f', connecting one end of the top with the end of the upper clamping-jaw, and a straight vertical side f², extending from the ⁷⁰ opposite end of the top to the upper side of the upper clamping-jaw. The head of the fastener when thus constructed is non-circular or rectangular. The opening e in the bottom of the wax-receiving box is made of the ⁷⁵ same non-circular or angular form as the adjusting-head, which enters the same, thereby preventing these parts from turning relatively to each other when assembled.

In the use of the wax-holder the jaws of ⁸⁰ the clamp are sprung apart and engaged with the edge of the ironing board or table within convenient reach of the operator, so that the adjusting-head is above the same, and the wax-box is slipped with its bottom opening ⁸⁵ over the adjusting-head until the upper end of the latter presses the wax - cake firmly against the woven covering, as shown in Fig. 2. The tension of the clamping-jaws is so adjusted that they grip the ironing - board ⁹⁰ sufficiently tight to hold the fastener and wax-receptacle firmly in place thereon. The wax-holder is now ready for use, and upon pressing the heated sad-iron against the top of the fabric covering the wax underneath ⁹⁵ the same will melt and pass through the meshes of the same and coat the face of the sad-iron. As the wax-cake gradually melts down and becomes reduced in height by the repeated application of the hot sad - iron ¹⁰⁰ thereto the inclosing box is at the same time lowered on the cake and the adjusting-head by the sad-iron, which overhangs the wax-cake and presses downward on the upper edge of the box while engaging the covered ¹⁰⁵ wax. Inasmuch as the box containing the wax is incapable of turning on the adjusting-head the wax and its support remain stationary, thereby permitting the sad-iron to be freely turned on the wax for applying the de- ¹¹⁰

sired coat of wax over the surface of the sad-
iron without liability of displacing the wax
and its holder.

In addition to securing the wax to the iron-
ing board or table the clamp may serve to
fasten the usual cloth J to the ironing-board,
which is used for cleaning or wiping the sad-
iron, this cloth being preferably clasped be-
tween the upper side of the ironing-board
10 and the upper jaw of the clamp, as shown by
dotted lines in Fig. 1.

I claim as my invention—

1. A wax-holder comprising a wax-recep-
tacle having an opening in its bottom, and
15 means for fastening said receptacle to a sup-
port and adjusting the wax in the same, com-
prising a clamp constructed to grip a support
and carrying a head which enters said open-
ing and bears against the wax in the recepta-
20 cle, substantially as set forth.

2. A wax-holder comprising a wax-recep-
tacle having an opening in its bottom, and
means for fastening said receptacle to a sup-
port and adjusting the wax in the same, com-
25 prising a pair of connected spring-jaws
adapted to grip a support and a head ar-
ranged on one of said jaws and entering the

opening in said receptacle, substantially as
set forth.

3. A wax-holder comprising a wax-recep-
tacle having an opening in its bottom, a disk
arranged loosely in the receptacle under-
neath the cake of wax, and an attaching-
30 clamp for the receptacle having an adjusting-
head extending through said opening and not
affixed to said disk, substantially as set forth.
35

4. A device for securing a wax-receptacle
to a support and adjusting the wax in the re-
ceptacle, consisting of a continuous strip of
metal which has one end bent to form upper
40 and lower clamping-jaws and a bow connect-
ing corresponding ends of said jaws while its
opposite end is bent to form a rectangular
head consisting of a flat top, a straight side
connecting one end of the top with the upper
45 jaw and another straight side extending
from the opposite end of said top toward said
upper jaw, substantially as set forth.

Witness my hand this 10th day of Febru-
ary, 1905.

KATHRINE ROHRDANTZ.
